UNITED STATES PATENT OFFICE.

CHARLES H. NICHOLS, OF DANSVILLE, NEW YORK.

DESIGN FOR A SUPPORTING-BRACKET FOR CULTIVATORS.

SPECIFICATION forming part of Design No. 31,717, dated October 24, 1899.

Application filed September 25, 1899. Serial No. 731,684. Term of patent 14 years.

To all whom it may concern:

Be it known that I, CHARLES H. NICHOLS, a citizen of the United States, residing at Dansville, in the county of Livingston and State 5 of New York, have invented and produced a new and original Design for Supporting-Brackets for Cultivators, of which the following is a specification.

The accompanying drawing is a perspective 10 view of a supporting-bracket for cultivators embodying my design.

The design consists of a supporting-bracket 15 for cultivators, such as shown in the accompanying drawing. The horizontal plate A is formed on its front end with a downwardly-projecting flange B, arranged at right angles to the plate A. At the lower end of the flange B there is a short forwardly-projecting flange C, having a curved front edge c and provided 20 with a curved slot c' between its front and rear ends. On the back end of the plate A there is a downwardly-projecting flange D, arranged at right angles to the plate A. On

the top of the plate, between its front and rear ends, there is a raised portion E, having 25 an inclined edge or periphery e and a central perforation e'. A rib e² extends centrally along the top of the plate A from the projection E to the rear end of the plate, and a similar rib e³ extends from the projection E 30 centrally along the plate A to near the front end of the plate A, where it joins curved ribs e⁴, which extend to the opposite front corners of the plate A and then extend down along the edges of the flange B and then forwardly 35 along the horizontal edges of the plate C.

I claim—

The design for a supporting-bracket for 40 cultivators, substantially as shown and described.

In testimony whereof I have hereunto subscribed my name.

CHARLES H. NICHOLS.
